US00D653003S

(12) **United States Design Patent**
Monroe

(10) **Patent No.:** US D653,003 S
(45) **Date of Patent:** ** Jan. 24, 2012

(54) **PET TAG**

(76) Inventor: **Sharon Gwyneth Monroe**, Pueblo, CO
(US)

(**) Term: **14 Years**

(21) Appl. No.: **29/315,297**

(22) Filed: **Jun. 12, 2009**

(51) **LOC (9) Cl.** 30-08

(52) **U.S. Cl.** D30/155

CLAIM

I claim the ornamental design for a pet tag, as shown and described.

DESCRIPTION

A portion of the disclosure of this patent document contains material which is subject to copyright protection. The copyright owner, Sharon G. Monroe has no objection to the facsimile reproduction by anyone of the patent document or the patent disclosure, as it appears in the Patent and Trademark Office patent file or records, but otherwise reserves all copyright rights whatsoever.

FIG. 1 is a perspective view of a pet tag showing my new design;

FIG. 2 is a front elevational view thereof;

FIG. 3 is a right side elevational view thereof (left side elevational view is a mirror view of the right side);

FIG. 4 is a rear elevational view thereof;

FIG. 5 is a top plan view thereof; and,

FIG. 6 is a bottom plan view thereof.

The broken line elements are not claimed.
